CHAIN-SAW SHARPENING TOOL

Richard T. Santore, Ansonia, Conn., assignor to
High Precision Incorporated, Hamden, Conn.

Filed Apr. 25, 1974, Ser. No. 464,221

Term of patent 14 years

Int. Cl. D8—05

U.S. Cl. D8—91

FIG. 1 is a perspective view of a chain-saw sharpening tool embodying the invention, looking from above and at an angle to one side thereof with the handle extending away;

FIG. 2 is a side view of the tool shown in FIG. 1 with an intermediate portion of the tool broken away and the outer end portion thereof being shown removed, the outer end portion thereof being moved toward the handle, the removed portion being identical extensions of the file and guide bar shown and the handle being the same shape all around except for a flat surface on the flange at the near end thereof, said flat surface being aligned with a corresponding flat surface on the spherical knob at the outer end of the file; and face on the spherical knob at the outer end of the file; and face on the spherical knob at the outer end of the file;

FIG. 3 is a cross-sectional view taken on the line 3—3 of FIG. 2 looking in the direction of the arrows, the

knob being spherical except for the flat surface shown in FIG. 2.

I claim:

The ornamental design for a chain-saw sharpening tool, substantially as shown and described.
